Primary Examiner — Karen S Acker

(57) **CLAIM**

The ornamental design for an floor mat, as shown and described.

DESCRIPTION

FIG. 1 is a perspective view of a floor mat showing my new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1;

FIG. 7 is a bottom view of the design shown in FIG. 1; and,

FIG. 8 is a perspective schematic view showing the floor mat of FIG. 1 in a position of use.

The broken lines in the drawing represent environmental subject matter that forms no part of the claimed design.

1 Claim, 8 Drawing Sheets
